UNITED STATES PATENT OFFICE.

HARRY MARSH, OF JAMESTOWN, NEW YORK.

ADJUSTABLE TIP-HOLDER FOR BILLIARD-CUES.

No. 908,021.

Specification of Letters Patent. Patented Dec. 29, 1908.

Application filed February 12, 1908. Serial No. 415,552.

To all whom it may concern:

Be it known that I, HARRY MARSH, a citizen of the United States, residing at Jamestown, in the county of Chautauqua and State of New York, have invented certain new and useful Improvements in Adjustable Tip-Holders for Billiard-Cues, of which the following is a specification.

My invention relates to devices for securing leather tips to billiard cues and particularly contemplates the provision of an improved device of this character for adjustably holding an elongated leather tip to a billiard cue, whereby said tip may be adjusted to compensate for the wear of the same.

My invention further and specifically resides in the following features of construction, arrangement and operation as will be hereinafter described with reference to the accompanying drawings, forming a part of this specification, in which like numerals are used to designate like parts throughout the several figures thereof, and in which—

Figure 1 is a side elevation of my improved device showing the same secured to the end portion of a billiard cue, Fig. 2 is a central longitudinal sectional view taken therethrough, Fig. 3 is a transverse sectional view taken therethrough on the line 3—3 of Fig. 1, Fig. 4 is a similar view taken therethrough on the line 4—4 of Fig. 1, and Fig. 5 is a perspective view of the clamping sleeve detached.

In the practical embodiment of my invention, and with particular reference to the accompanying drawing I provide a billiard cue A with a reduced end B, on which reduced end B I mount a clamping sleeve 1 extending outwardly from said cue A and shown particularly in Fig. 5. Within the clamping sleeve 1 I preferably arrange a cylindrical tube 2 having its closed end 3 abutting the end of the reduced portion B of the cue A and attached thereto by a screw or the like 4. The clamping sleeve 1 is provided with a pair of oppositely disposed openings 5 cut therethrough at an approximately central point and is further provided with longitudinal slots 6 extending from its outer end for a distance towards said openings 5, and forming therebetween a plurality of spring tongues 7 having beveled ends 8. The clamping sleeve 1 is further provided with a threaded portion between the inner ends and the slots 6 and the openings 5 upon which the internally threaded end of an operating sleeve 9 is

adapted to engage, said operating sleeve 9 being provided with a contracted outer edge 10 adapted to engage upon the beveled ends 8 of the spring tongues 7 to force the same 60 into engagement with an elongated leather cue tip C to hold the same firmly in position.

The end of the cylindrical tube 2 within the clamping sleeve 1 extends to a point within said sleeve at one side of the opening 5, while at the opposite side of said opening 5 I preferably arrange a circular internal flange 11, between which and the end of the tube 2 I arrange a rotatable nut 12 having a roughened circumferential face. The nut 12 is 70 provided with a central internally threaded bore through which a threaded stem 13 projects from a circular plate 14 having outwardly extending lugs 15 arranged to slide within opposite ones of the longitudinal 75 slots 6 within the clamping sleeve 1. The circular plate 14 abuts the inner end of the cue tip C and, being held from rotation by means of its lugs 15 engaging within the slots 6, rotation of the nut 12 causes a longitudinal displacement of the threaded stem 13 and its plate 14 and the cue tip C, forcing said tip outwardly or moving inwardly dependent upon the direction of such rotation, the nut 12 being held from sidewise movement between the end of the cylindrical tube 2 and the circular internal flange 11 of the clamping sleeve 1.

It will be understood that in assembling the device the nut 12 is inserted in position 90 within the clamping sleeve 1 before said sleeve is forced over the cylindrical tube 2 and the contracted end of the cue A. It will further be understood that when longitudinal movement of the cue tip C is desired the operating sleeve 9 is first slightly unscrewed from the clamping sleeve 1 allowing the spring tongue 7 thereof to withdraw slightly from tight engagement with said cue tip, said operating sleeve 9 being provided with 95 roughened bands 16 extending therearound for more conveniently manipulating the same.

Having thus fully described my invention, I claim:

1. In a cue tip holder of the character described, the combination of a clamping sleeve adapted to fit the end of a cue and having centrally disposed aligned openings therethrough and a plurality of spring 110 tongues extending from the outer end thereof, said spring tongues being adapted to hold.

a cue tip slidably therein, an operating sleeve for engagement upon said clamping sleeve and provided with a contracted end to force said spring tongues into engagement with 5 said tip, a rotatable nut mounted within said clamping sleeve opposite said alined openings, and provided with a threaded bore, means to prevent sidewise movement of said nut therein, said means assisting in securing 10 said clamping sleeve to the end of the cue, a threaded stem extending through said threaded bore in said nut and carrying a plate upon its outer end, said plate abutting the rear end of said cue tip and having laterally extending 15 lugs projecting between pairs of said spring tongues to prevent rotation of said plate and said threaded stem, whereby longitudinal movement will be imparted to the same upon the rotation of said nut, substantially as de- 20 scribed.

2. In a cue tip holder of the character described, the combination with a cue having a reduced end, of a threaded clamping sleeve adapted to fit the said reduced end of said 25 cue, and having centrally disposed alined openings therethrough and a plurality of spring tongues extending from the outer end thereof, said spring tongues being adapted to

hold a cue tip slidably therein, an operating sleeve threaded to screw upon said clamping sleeve and provided with a contracted end to force said spring tongues into engagement with said tip, a rotatable nut mounted within said clamping sleeve opposite said alined openings and provided with a threaded bore, means to prevent sidewise movement of said nut therein, said means being secured in part to the said reduced end of 35 said cue and assisting in securing said clamping sleeve thereto, a threaded stem extending through said threaded bore in said nut and carrying a plate upon its outer end, said plate abutting the rear end of said cue tip and having laterally extending lugs projecting 40 between pairs of said spring tongues to prevent rotation of said plate and said threaded stem, whereby longitudinal movement will be imparted to the same upon the rotation of said nut, substantially as de- 45 scribed.

In testimony whereof I affix my signature in presence of two witnesses.

HARRY MARSH.
